UNITED STATES PATENT OFFICE.

ALFRED B. LOUISON, OF ROCKFORD, ILLINOIS.

CRUTCH.

1,342,506.

Specification of Letters Patent.

Patented June 8, 1920.

Application filed February 24, 1919. Serial No. 278,605.

To all whom it may concern:

Be it known that I, ALFRED B. LOUISON, a citizen of the United States, residing at Rockford, in the county of Winnebago and State of Illinois, have invented a certain new and useful Improvement in Crutches, of which the following is a specification.

The invention relates to crutches, and has for its object the provision of means of a practical character for minimizing the wear upon the clothing of the user and at the same time facilitating the use of the crutch.

The object of the invention thus generally stated is attained by the construction and arrangement illustrated in the accompanying drawings forming part hereof, in which Figure 1 is a fragmentary side elevation of the upper portion of a crutch embodying the features of my invention. Fig. 2 is an enlarged sectional view taken on line 2—2 of Fig. 3. Fig. 3 is a transverse sectional view taken on line 3—3 of Fig. 2. Fig. 4 is a fragmentary edge elevation of the upper portion of the crutch.

In the embodiment of the invention illustrated, the crutch comprises a staff having crutch sticks 1, a top-piece 2, and a bearing member 3 mounted upon the upper end of the crutch sticks. 4 indicates generally means for retaining the top-piece in position upon its bearing member.

The crutch sticks 1 may be of usual construction, and the bearing member 3 is provided in its under side with openings 5 to receive the upper ends of the crutch sticks.

The top-piece 2 is preferably curved on a radius of substantial length so as to enable an easy rolling motion to be effected between it and the bearing member 3 which has a straight upper surface. By this construction it will be apparent that in the use of the crutch, as the crutch staff is swung to and fro with reference to the top-piece, which is held relatively stationary by the user, the bearing point of the top-piece upon the member 3 is constantly shifted according to the angular position of the crutch and in a direction toward the vertical. Thus the weight upon the crutch tends at all times to approach a position in which it can be supported with the least effort on the part of the user. Preferably the contacting surfaces of the top-piece 2 and the bearing member 3 are provided with intermeshing teeth 6 and 7 which serve to pre-

vent relative endwise sliding movement between said parts.

The means 4 is adapted to hold the top-piece 2 in position upon the member 3 without preventing the relative rolling or rocking motion therebetween. Such means preferably comprises a bolt or rod 8 having a flattened upper portion entered through a slot 9 in the member 3 and into an arcuate recess 10 in the top-piece 2, being pivoted in said recess at 11. A compression spring 12 bearing between the member 3 and a wing nut 13 threaded on the lower end of the rod, yieldingly holds the top-piece in position upon the member 3. The upper end of the spring 12 preferably bears upon a slotted washer 14 engaging with the under side of the member 3 and at its other end upon a washer 15 supported by the wing nut 13. It will be seen that the means 4 does not prevent the desired relative motion between the top-piece 2 and the member 3, but serves to limit the extent of such movement in either direction, the spring being preferably so tensioned as to normally hold the top-piece 2 in its central position upon the member 3, without restraining to any material extent the normal movements between said parts. The tension of the spring may, however, be readily adjusted by the user to suit his own convenience.

For the purpose of preventing the clothing of the user from being caught and bound between the top-piece 2 and the member 3, suitably shaped plates 16 of preferred material are secured on opposite sides of the top-piece 2. If desired, these plates may be made of rigid material so as to serve as guide members for the relatively moving parts 2 and 3; and in order to further enclose such parts and to hold said plates more rigid, end pieces 17 may be provided between the plates, the lower corners of the bearing member 3 being shaped as at 18 to permit the relative movement set forth.

It will be seen that I have produced a crutch of a very practical character. The top-piece is mounted in such a manner that it does not interfere with the easy use of the crutch, but on the contrary, facilitates such use. At the same time it materially decreases the wear upon the clothing of the user, which accompanies the use of the ordinary crutch, making it possible to use to advantage a cushion upon the top-piece.

While the invention is illustrated and described herein with considerable particularity, it will be understood that I do not intend to be limited in the interpretation of the appended claims except as may be necessitated by the state of the prior art.

I claim as my invention:

- 5 1. A crutch having, in combination, a top-piece, a bearing member for the top-piece, said top-piece and bearing member being shaped to permit relative rolling motion therebetween and having intermeshing teeth, a rod pivoted at one end to said top-piece and having a nut on its other end, a spring bearing between said nut and said bearing member, said bearing member having a central slot therein through which said rod extends, and plates secured on opposite sides of the top-piece and adapted to inclose substantially the moving parts.
- 10 2. A crutch having, in combination, a top-piece, a bearing member for the top-piece, said top-piece and bearing member being shaped to permit relative rolling motion therebetween, a rod pivoted at one end to said top-piece and having a nut on its other end, and a compression spring bearing between said nut and said bearing member.
- 15 3. A crutch having, in combination, a top-piece, a bearing member for the top-piece, said top-piece and bearing member being shaped to permit relative rolling motion therebetween and having intermeshing teeth, and means for yieldingly retaining the top-piece in position upon the bearing member.
- 20 4. A crutch having in combination, a fixed member carried by a staff, a top member and a connection between the top member and said fixed member, at least one of the contacting surfaces of said members being

curved, and said connecting means being adapted when the crutch is in use to permit of a relative rolling motion therebetween with a shifting of the bearing point between 45 said members along substantially the entire length of the fixed member.

5. A crutch having, in combination, a top-piece having a curved lower surface, a bearing member having a substantially straight 50 upper surface upon which the top-piece is adapted to bear, and means for retaining the top-piece in position upon the bearing member and adapted to permit relative rolling motion between the top-piece and bearing member, said contacting surfaces being provided with intermeshing teeth to prevent relative endwise movement between the top-piece and the bearing member.

6. A crutch having, in combination, a top-piece, a bearing member, and spring means connecting said top-piece and bearing member and permitting the bearing member to roll upon the top-piece while the latter is held stationary, said means being adapted 65 to limit the extent of such movement of the bearing member.

7. In a crutch, the combination with a staff, of a fixed member, a top member, and means for retaining said top member on said 70 fixed member adapted when the crutch is in use to permit of a relative rolling motion therebetween so that the point of support for the top piece moves in the swinging of the staff substantially along the entire length 75 of the fixed member depending upon the extent of swinging movement of the staff relative to the top piece.

In testimony whereof I have hereunto set my hand.

ALFRED B. LOUISON.
